(57) **CLAIM**

The ornamental design for a ceiling fan hanger assembly as shown and described.

DESCRIPTION

FIG. 1 is a top perspective view of a ceiling fan hanger assembly showing our new design in the environment of a ceiling fan;

FIG. 2 is an exploded perspective view of the ceiling fan hanger assembly of FIG. 1;

FIG. 3 is a side elevation view of the ceiling fan hanger assembly of FIG. 1; and,

FIG. 4 is an enlarged view of detail 4 encircled in FIG. 3. Broken lines illustrate portions of the ceiling fan hanger assembly that form no part of the claimed design. Additional broken lines in FIG. 1, showing a ceiling fan, illustrate environmental subject matter and form no part of the claimed design.
